UNITED STATES PATENT OFFICE.

WILLIAM W. GILES, OF WASHINGTON, DISTRICT OF COLUMBIA.

VELOCIPED.

SPECIFICATION forming part of Letters Patent No. 252,455, dated January 17, 1882.

Application filed October 31, 1881. (No model.)

To all whom it may concern:

Be it known that I, WILLIAM WHEATON GILES, of Washington, in the District of Columbia, have invented a new and useful Improvement in Velocipedes; and I do hereby declare that the following is a full and accurate description of the same.

This invention relates to that class of velocipedes which have more than two wheels—commonly three wheels—and known as "tricycles," and it has special reference to that description of tricycle for which Letters Patent were issued to me January 11, 1881, wherein the propelling power derived from the muscular action of the legs is supplemented by hand-levers to be worked by the hands and arms, and the steering-gear is controlled by movements of the seat in a plane transverse to the line of progression.

The improvements hereinafter particularly described relate, first, to the manner of controlling the steering-gear by the movement of a lever independent of the seat in a plane transverse to the line of progression; second, in the manner of operating the brake by means of a vibrating back lever against which the rider may lean; third, in the structure of the forked frame.

That others may fully understand my improvements I will particularly describe them, having reference to the accompanying drawings, wherein—

Figure 1 is a plan of my tricycle. Fig. 2 is a perspective view, showing the structure of the steering and brake gear. Fig. 3 is a longitudinal sectional elevation. Fig. 4 is a similar elevation, showing a modification. Fig. 5 is a plan of the same. Fig. 6 is a perspective detail. Fig. 7 is a front elevation of the axle. Fig. 8 is longitudinal section of a wheel-hub. Fig. 9 is a perspective, showing adjustability of the side arms.

A is the frame of my machine, and B B are the main supporting-wheels. C is the steering track-wheels.

The frame A is preferably made curved or crescent-shaped with the seat placed at the re-entrant portion, and the axles for the wheels located at or near the extremities. The advantage of employing a frame of this form is in the facility it affords for placing the seat low

down and the driving crank-shaft below the level of the wheels' axis; but as for some reasons it is not always desirable to be near the ground it is not essential that the frame shall be of the form shown.

At the center of the frame A there is a suitable box-bearing, a, to receive the end of the arm D of the trailing-wheel C. This arm I prefer to make tubular, not only for the purpose of securing the greatest strength in proportion to the material employed, but to afford a protected way for the passage of the cord or wire whereby the brake E may be operated. The forward end of the arm D rests and turns in the box a, and at a point nearer the wheel C there is another box, b, for said arm, and said box b is supported by braces d, which are attached to the frame. A collar, e, upon the arm D above the box b, will prevent endwise slip of said box on the arm. The brace-rods d need not be heavy, because the strain upon them is entirely tensile.

With this organization it will be observed that the machine has three points of support upon the ground, and that the arm of the near wheel is oblique to the horizon, so that if said arm be partly rotated the direction of the plane of the wheel C will be changed as to the planes of the wheels B B—that is to say, when the wheel C stands upright its plane will be vertical and parallel with the planes of wheels B B, but when the arm D is partly rotated the plane of wheel C becomes inclined and oblique to the planes of wheels B B. It therefore may be caused to steer the vehicle by employing instrumentalities whereby the rider can control the position of the wheel C. This control I propose to effect by placing said arm in immediate contact with the person of the rider, so that by swaying his body to the right or left he may cause said arm to be rotated in a corresponding direction. There are several ways for accomplishing this connection. The seat F may be mounted directly upon the end of the arm D, so that the portions of it on each side of said arm will act as levers to receive the rider's weight as he leans to the right or left; or the seat may be rigid, and the arm D may be provided with two arms or levers, which extend upward and rest against the rider's sides; or if, as will sometimes be the case, it is

desirable to provide for a larger range of motion than is convenient to give it by a single direct-acting lever like the tipping seat, then a multiplying device may be interposed between 5 the prime lever in contact with the person and the arm D. Such a device is shown in Fig. 2, wherein the rider's sides are in contact with the arms G G, which are attached to the shaft H; and capable of imparting a rotating motion 10 to it. The forward end of the shaft H is bent downward, as at J, and engages with the outer end of an arm, I, which projects laterally from the arm D. By this means the relative motions of the shafts H and D may be varied, because 15 the greater the relative length of crank part of H the greater will be the relative movement of the arm D.

It is highly important in a machine employing both hands and feet for its propulsion that 20 the brake may be controlled otherwise than by hands or feet, and I have therefore provided a vibrating lever behind the seat, which, when the body leans backward, will be caused to draw forward the cord or rod J, whereby 25 the brake E is operated. This lever is shown in the drawings at K, and bearing at its top the side arms, G G. It is pivoted transversely to the rock-shaft H, and therefore does double duty as a steering-lever when passed sidewise 30 and a brake-lever when pressed backward; but it is evident that these separate functions may be exercised by separate levers, if desired.

In the machine as shown in the drawings the foot-treadles are below the level of the 35 wheels' axis, and the frame A is extended forward and downward far enough to receive the boxes g, in which the treadle crank-shaft L revolves. The shaft L is bent so as to constitute cranks for the feet and also for the hand-lever m; but as these parts do not in themselves present novelty in this case no further 40 description is required.

Figs. 4, 5, and 6 are introduced merely for the purpose of showing how my vibrating back 45 to operate the brake and my side braces moving in a plane transverse to the line of progression may be applied to a machine having a steering-wheel mounted upon an arm with a vertical pivot.

50 The rock-shaft H and vibrating arm k are the same as above described, but the shaft H, instead of acting to rotate the trailing-wheel arm C', acts upon a bell-crank, N, and through said bell-crank and the rod p upon the short laterally-projecting tiller-arm A', which 55 controls the steering-wheel and its spindle.

The seat F may be mounted upon two adjustable rods, f f, so that it may be raised and lowered, as desired, and springs may be applied to it in the usual way, as desired.

The frame may be constructed with a drooping axle, as shown in Fig. 7, and that form will impart strength by relieving the joint between the axle part and the reach from the torsion to 65 which it is subjected in the ordinary form, where the bent part of said axle is in a horizontal plane.

The cross-arm P serves as supports for the hand-levers M.

In Fig. 8 the structure of the hub of the 70 wheel B is shown. The inner face of said hub is furnished with a circular row of ratchet-teeth, t, and a hub, R, similarly furnished, is mounted loosely upon the wheel-spindle, and in engagement with said hub. The driving-chain S runs 75 upon said hub R, and transmits motion from the crank L, and thereby the wheel B is propelled. The hub R is loose upon its spindle, and is kept in engagement with the wheel hub by a spring, T. It is also provided with suitable mechanism, whereby it may be drawn away from and out of engagement with the wheel B, and the latter is then free. If both wheels B are provided with driving-chains, the driving power will be transmitted to both 80 wheels while the machine is running in a straight course; but in passing around curves the inner wheel will be the driver, and the outer wheel will run faster than its driving-hub R. Said hub will then give back automatically to let the ratchet teeth pass each other. 85

In Fig. 9 adjustability of the arms G G, both vertically and horizontally, is shown.

In Fig. 3 lever K is shown with a joint at u, so that, when said lever moves laterally with 90 the shaft H, its extremity may remain in line with the arm D.

Having described my invention, what I claim as new is—

1. In a tricycle, an arm projecting from the 100 frame and capable of partial revolution around an oblique axis, and a steering-wheel mounted on said arm at its extremity, combined with means whereby movements of the rider's body in a vertical plane transverse to the line of 105 progression will cause a rotation of said arm and control of the steering-wheel, as set forth.

2. In a tricycle, an arm projecting from the frame and capable of partial rotation around an oblique axis, and a steering-wheel mounted 110 on said arm at its extremity, combined with a side lever independent of the seat and moving on a horizontal axis, against which the rider leans in a vertical plane transverse to the line 115 of progression, whereby said arm may be rotated and the steering-wheel controlled, as set forth.

3. In a triycle, a steering-wheel mounted at the outer end of an oblique arm which is capable of partial revolution on its axis, whereby the plane of said wheel can be parallel with the planes of the main bearing-wheels or be deflected in either direction therefrom, combined with a side lever against which the rider leans in a plane transverse to the line of progression, and a multiplying device interposed between said side lever and said oblique arm to increase the relative motion of the latter and control the steering-wheel, as set forth. 120

4. In a tricycle, a steering-wheel, C, mounted 125 at the extremity of an oblique arm, D, which is capable of partial revolution upon its axis, and provided with the arm I, combined with the rock-shaft having one end turned downward

and engaged with said arm I, and the side braces, G, mounted upon said rock-shaft, whereby the rider may control the steering-wheel by swaying his body in a plane transverse to the line of progression.

5. In a tricycle-frame, A, provided with a box, a, attached to said frame, an oblique arm, D, which turns in said box at its forward end and bears the steering-wheel C at its rear end, combined with a box, b, fitted to said arm nearer its wheel end, and side brace-rod, d, whereby said box b is restrained from motion toward the box a, as set forth.

6. In a tricycle, a brake-lever, E, and its actuating cord or rod, combined with a vibrating lever placed so that said brake will be pressed against the wheel by a backward motion of the rider's body in contact with said vibrating lever.

20 7. In a tricycle, a steering-wheel and a brake, combined with a rock-shaft, H, a lever, K, pivoted thereon and extending up near the rider, and provided with side arms or braces, G, and means for connecting said rock-shaft and lever with the steering gear and brake respectively, whereby the same lever, K, may be caused to actuate the steering-gear or the brake at will.

25 8. In a tricycle, a frame, A, having its ends

bent forward to receive and hold the axles for the wheels and treadle-shaft in advance of the seat, combined with a rearward-projecting arm oblique to the horizon, and capable of partial rotation on its axis to control a steering-wheel mounted on the rear end of said arm.

30 9. In a tricycle, the wheel B, provided with ratchet teeth t, combined with a ratchet-hub, R, in engagement therewith, and the driving-chain S on said hub R, and motor crank-shaft below the level of said hub, whereby the wheel B may be liberated from the driving power by withdrawing said hub R from engagement, as set forth.

35 10. In a tricycle, a steering-gear operated by movements of the rider's body in a plane transverse to the line of progression, combined with the side arms, G, adjustable vertically and horizontally, so as to be fitted to the rider, as set forth.

40 11. In a tricycle, the steering-gearing, with its controlling-shaft H, combined with the lever K pivoted to said shaft and provided with the joint at u, for the purpose set forth.
